DUPLICATING APPARATUS

Hubert Jagger, Chicago, Ill., assignor to Ditto,
Incorporated, Chicago, Ill., a corporation of
West Virginia

Application August 22, 1938, Serial No. 226,081

9 Claims. (Cl. 101—133)

My invention relates to duplicating apparatus in which a hectograph pad secured removably in position on the face of a flat bed is provided with a design of typewritten matter or the like formed in reverse thereon by the use of copy ink, the apparatus comprising an impression roller or other suitable means for pressing copy sheets one at a time into engagement with the pad for transferring a small fractional portion of the ink to each of the copy sheets in turn for producing the printed matter or other design in positive thereon.

My invention comprises improved means for securing the hectograph pad removably in position on the bed of the machine; improved means for insuring a ready application of the copy sheets successively in operative position on the bed of the machine; improved means for applying the required pressure on the face of the copy sheet for securing the desired impression thereon; and an improved form and arrangement of frame and carriage parts generally by which a strong construction shall be provided, capable of being used to advantage by operators having little mechanical knowledge or skill. It is a further object of my invention to provide an arrangement of very simple construction from the standpoint of production and assembly of the parts, and one which can be produced easily on a commercial basis at a comparatively low cost of manufacture.

It is another object of my invention to improve apparatus of this type in sundry details hereinafter pointed out. The preferred means by which I have accomplished my several objects are illustrated in the accompanying drawings, in which—

Fig. 1 is a top plan view of my improved duplicating machine.

Fig. 2 is a side elevational view of the machine of Fig. 1.

Fig. 3 is a top plan view of one end portion of the machine of Fig. 1, but shown on a considerably enlarged scale, with the carriage portion of the machine in changed position, and with some of the parts broken away for clearness of illustration.

Fig. 3a is a sectional elevation taken along lines 3a—3a of Fig. 3.

Fig. 4 is a transverse vertical sectional view taken on an enlarged scale at the line 4—4 of Fig. 3.

Fig. 5 is a longitudinal vertical sectional view taken on the line 5—5 of Fig. 3, but with a

hectograph pad in position on the bed of the machine.

Fig. 6 is a vertical cross sectional view taken substantially at the line 6—6 of Fig. 4.

Fig. 7 is a longitudinal vertical sectional view taken on the line 7—7 of Fig. 1, but with the carriage removed and with a hectograph pad secured on the machine, the middle portion and both ends of the machine being broken away.

Fig. 8 is a bottom plan view of a fragmentary portion of the machine, with certain of the parts shown by dotted lines in changed position.

Fig. 9 is a vertical sectional view taken substantially at the line 9—9 of Fig. 7, but with the hectograph pad omitted.

Fig. 10 is a top face view of the retaining strip by which the slide plate is held adjustably in position for securing the hectograph pad on the machine.

Fig. 11 is a top face view of a fragmentary portion of the slide plate showing its arrangement for cooperation with the retaining strip; and

Fig. 12 is a top face view of a fragmentary portion of the hectograph pad as shown in Figs. 25 and 7.

Referring now to the several figures of the drawings, in which corresponding parts are indicated by the same reference characters, 15 indicates the bed of my improved machine which in the arrangement shown is formed of sheet metal having downwardly turned flanges 16, 17, 18 and 19 at its side edges as is best indicated in Fig. 1. In the arrangement shown, the bed 15 is reinforced at opposite sides by means of angle bars 20 and 21 fixedly secured to the flanges 17 and 19 respectively, as is best shown in Fig. 4. In the arrangement shown, the bed is supported in position by supporting blocks 22 at opposite corners of the machine, the rear blocks 22 being mounted upon arms 23 formed integrally with the flanges 17 and 19, and the supporting blocks 22 at the forward end of the machine being supported by brackets 24 fixedly connected to the outer faces of the angle bars 20 and 21, as is clearly shown in said Fig. 4. In the preferred arrangement, the blocks 22 are made of rubber in the form of suction cups which serve to grip a table upon which the machine is placed.

As is clearly shown in Fig. 1, the angle bars 20 and 21 are provided at their ends with turned end portions 25 positioned transversely with respect to the bars, such transversely disposed end portions having plates 26 connected therewith for rigidly mounting slide bars 27 and 28 in posi-

15

tion along the sides of the machine, the bars 27 and 28 being mounted in parallel relation to each other and being disposed in slightly spaced relation to the outer edges of the angle bars 20 and 21. Upon the slide bars 27 and 28, I have provided slide blocks 29 and 30 respectively, which have a snug working fit on said bars so as to be readily shiftable back and forth along said bars. As is best shown in Fig. 1, the bars 27 and 28 are provided with buffer blocks 31, preferably of rubber, to serve as stops for limiting the movement of the slide blocks upon the bars.

The slide blocks 29 and 30, in the arrangement shown, are connected by means of a transversely disposed carriage 32 which is adapted to be moved longitudinally of the machine upon the slide bars 27 and 28. As is best shown in Fig. 5, the slide blocks 29 and 30 are of such length as to afford an effective bearing upon the slide bars 20 so as to insure ready movement of the carriage upon the slide bars without any substantial tendency of the parts to bind upon the bars. In the arrangement shown, the carriage 32 comprises end frame members 33 and 34 formed of sheet metal in the form of housings, the lower edge portions of the end plates of such housings being connected by means of bolts 35 with the slide blocks, as is best shown perhaps in Figs. 2 and 5. As is clearly shown in Fig. 4, the bolts 35 by which the slide block 29 is connected to the frame member 33 fit snugly in the openings in the wall portion so as to hold the slide block 29 rigidly in position. The bolts 35 by which the slide block 30 is connected with the end frame member 34, however, have a loose fit in the openings through the end wall of the housing member 34 so as to provide for a limited amount of play between the slide block 30 and the housing member 34, the bolts 35 being provided with enlarged shoulders for insuring the loose connection of the parts.

The carriage 32 comprises further a transversely disposed plate 36 which is provided at its forward edge with a downwardly turned flange portion 37 and is provided at its ends with upwardly turned end portions 38, as is best shown in Fig. 5. The downwardly turned flange 37 extends between the upwardly turned end portions 38 of the plate, as is best shown in Fig. 3, such end portions projecting into the housing members 33 and 34 where they are rigidly secured by welding or otherwise for securely connecting the end housing portions with the transverse plate portion 36. The plate 36 is further connected with the end housing members by means of angle bars 39 secured by welding or in any other suitable manner to the upwardly extending plate portions 38 and to the upper wall portions of the housing members 33 and 34 (see Fig. 4).

By the use of my improved construction as above described, the carriage 32 is made very strong while being comparatively light in weight and is very readily shiftable along the bars 27 and 28 as may be desired in the use of the machine.

The carriage 32 comprises further a transversely extending bar or bracket 40 which in the arrangement shown is formed by casting in the shape of a yoke comprising heavy downwardly extending arms 41 and 42, as is best shown in Fig. 4. The downwardly extending arms 41 and 42, in turn, are provided with forwardly extending arms 43 and 44, as is clearly shown in Fig. 3. The bracket as a whole is mov-

ably mounted in position by means of bolts 45 extending through the arms 43 and 44 and through the upwardly extending plate portions 38 of the transverse plate 36, as is best shown in Fig. 3, the arrangement being such that the bracket 40 is adapted to swing easily about the axis of the bolts 45 which are mounted in alignment with each other. Between the downwardly extending arms 41 and 42 of the bracket, I have rotatably mounted an impression roller 46 by the use of any suitable means by which the roller is enabled to have the desired rotary movement. At its ends, the bracket 40 is provided with outwardly extending pins or lugs 47 which are connected by means of coiled springs 48 with lugs 49 struck from the transverse plate 36, the arrangement being such that the springs 48 normally hold the bracket 40 turned into the position as shown in Fig. 5, with the roller 46 in raised position with respect to the bed plate 15.

The means for mounting a hectograph pad in position upon the machine comprises a retainer strip 50 which is secured in position upon the bottom face of the bed plate 15 by welding or in any other suitable manner. As is clearly shown in Figs. 7 and 10, the retainer strip 50 is provided with a downwardly turned end portion 51, and with outwardly extending lugs 52 along its sides, the lugs 52 being offset downwardly with respect to the strip, as is best shown in Fig. 9. A slide plate 53 is slidably mounted in position upon the bottom face of the bed plate 15 by means of the retaining strip 50, such plate 53 being provided with a slot 54 therein of slightly greater width than that of the strip 50, being provided with notches 55 adapted to be entered over the lugs 52 for the assembly of the parts into the position as shown in Figs. 7 and 8, so that the plate 53 is supported in position directly upon the lugs 52 as shown in Fig. 9. At its rear end, the plate 53 is provided with a downwardly turned flange 56, and a coiled spring 57 is interposed between said flange 56 and the turned end portion 51 of the retainer strip 50, such spring 57 serving at all times to urge the plate 53 forwardly toward the right in Figs. 7 and 8.

Means is provided for moving the plate 53 toward the left in Figs. 7 and 8 against the action of the spring 57. Such means comprises a cam 58 pivotally mounted upon a bolt 59 mounted in the bed plate 15 and extending through the slot 54, such cam being of appreciably greater length than width, as is clearly shown in Fig. 8. A handle 60 is provided on the cam 58 for turning the cam from the position as shown in solid lines in Fig. 8 to the position as shown in dotted lines, the arrangement being such that the engagement of the end of the cam with the plate 56 serves effectively for holding the cam in its longitudinal position as shown in dotted lines in Fig. 8 when it is swung from the transverse position as shown in solid lines in said figure.

The machine as above described is designed for use in connection with a hectograph pad 61 of well-known standard form as is best shown in Fig. 12, such pad comprising a strip of fabric 62 covered on one face with a layer of gelatin 63 of any approved type. At its ends, the fabric 62 is provided with openings 64 therein in spaced relation transversely of the sheet, a hook member 65 formed of sheet metal bent into shape being mounted upon the end of the fabric closely adjacent to the openings 64. The rear edge portion of the bed plate 15 is arranged for cooperation with the pad 61, being provided with up-

wardly extending tongues 66 in spaced relation thereacross corresponding to the position of the openings 64 in the pad. In the arrangement shown, the tongues 66 are struck from the metal 5 of the flange 16, such tongues 66 having upwardly extending end portions in alignment with each other transversely of the machine serving to act as a margin stop for a sheet of paper inserted upon the plate 36 of the carriage and extending 10 underneath the impression roller 46. As will be readily understood, the pad 61 is capable of being secured very quickly in position, the openings 64 being inserted over the tongues 66 so as to permit 15 the hook member 65 to be engaged about the bottom edge of the flange 16 of the bed plate.

At the forward end of the machine, at the right in Figs. 1 and 8, the flange 18 is provided with a series of slots 67 through which extend tongues 68 formed on the front edge of the plate 53, such 20 slots serving as a guide for the plate 53 as it is moved back and forth with respect to the bed plate. The arrangement of the parts is such that when the lever 60 stands in the position as shown in dotted lines in Fig. 8 so as to hold 25 the plate 53 in the dotted line position, a hectograph pad 61 having its rear edge connected with the flange 16 as shown in Fig. 7 is capable of having the hook member 65 on its opposite end portion brought readily into engagement with the ends of the tongues 68. The arrangement is such that when the lever 60 is swung again 30 into the position as shown in solid lines in Fig. 8 the spring 57 moves the plate 53 into position for tightening the pad 61 upon the bed plate as 35 shown in said Fig. 7.

Across the carriage 32 opposite the impression roller 46, I have provided a guard plate 69 which is attached at its ends to the housing members 33 and 34, serving thus both as a guard and as 40 a transverse strengthening member.

At about the middle portion of the yoke comprising the crossbar 40, I have provided a pressure plate 70 which in the arrangement shown is formed integrally with the bar 40, being obliquely 45 disposed, as is best shown in Fig. 5, so as to be in convenient position for the application of pressure downwardly and forwardly thereon.

Upon the transversely extending plate 36 of the carriage 32, I have provided paper guide devices 71 and 72 which are adjustable transversely of the machine to accommodate different widths of copy sheets to be employed on the machine. In the arrangement shown, the guide plates 71 and 72 are mounted in position by 55 means of bolts 73 extending through openings in the members 71 and 72 and through slots 74 extending across the machine longitudinally of the downwardly extending flange 37 of the plate 36.

With a hectograph pad 61 in position upon the bed plate 15, and with a suitable design made from copy ink and applied in any suitable way to the pad 61, a copy sheet is inserted in position upon the plate 36 between the paper guide devices 71 and 72, such sheet being slid underneath the roller 46 so as to be brought into normal position by engagement with the upwardly extending tongues 66. Pressure is then applied 65 downwardly upon the pressure plate 70 for press-

70 sing the copy sheet firmly into engagement with the pad 61, whereupon pressure is applied forwardly upon the plate 70 for moving the carriage 32 toward the right in Fig. 5, serving to press the copy sheet into effective engagement 75 with the pad 61 throughout substantially the full

length of the sheet. The extreme forward end of the sheet is preferably left out of engagement with the pad so as to enable the operator to grasp the sheet readily for stripping it from the pad 61 after the carriage 32 has been returned to the 5 extreme left into the position as shown in Fig. 5. The mechanism is then ready for the insertion of a new copy sheet and a repetition of the operation as above described.

By the use of my improved construction, I 10 have provided a machine which is very simple in operation and which can be employed very conveniently, one which can be produced easily and cheaply upon a commercial basis, and one which is highly effective in use. It is to be 15 understood that I prefer to employ the form and arrangement as shown in the drawings and as above described, but that the invention is not to be limited to such form and arrangement except so far as the claims may be so limited, the 20 construction being susceptible to changes without departing from my invention.

I claim:

1. In a duplicating apparatus, the combination of a flat bed, means for securing a hectograph pad removably in position on said bed, slide bars secured in parallel relation to each other along opposite sides of said bed, supporting blocks slidably mounted on said bars, a carriage extending across said bed and supported 25 at opposite sides of the machine by said blocks, a roller rotatably mounted on said carriage and movable thereon into and out of operative impression relationship to a hectograph pad on said bed, yielding means adapted normally to 30 hold the roller out of operative position with respect to said hectograph pad, means movably mounted on said carriage adapted by pressure downwardly and forwardly thereon to cause said roller to press against said pad and to move 35 longitudinally of the machine over the face of the pad and resilient means engaging the forward end of said hectograph pad to tension the same and to take up any slack caused in the pad by said downward and forward pressure on 40 said roller.

2. In a duplicating apparatus, the combination of a flat bed, means for securing a hectograph pad removably in position on said bed, slide bars secured in parallel relation to each 45 other along opposite sides of said bed, supporting blocks having a snug sliding fit on said bars, a carriage extending across said bed having a rigid connection with the supporting block at one side and a loose connection with the supporting block at the opposite side for permitting said carriage to have free movement along said bars, a single roller rotatably mounted on said carriage and movable thereon into and out of 50 operative relation to a hectograph pad on said bed, yielding means adapted normally to hold the roller out of operative position with respect to said hectograph pad, and means for pressing said roller downwardly and for moving it forwardly along the pad, comprising an arm extending upwardly from the roller and a pressure plate in oblique position on said arm for convenient application of pressure downwardly and forwardly 55 thereon.

3. In a duplicating apparatus, the combination 60 of a flat bed, means for securing a hectograph pad removably in position on said bed, slide bars secured in parallel relation to each other along opposite sides of said bed, supporting blocks slidably mounted on said bars, a carriage extending 65

across said bed and supported at opposite sides of the machine by said blocks, a bracket substantially in the form of a yoke having downwardly disposed arms at its end portions, a single roller rotatably mounted between said downwardly extending arms, other arms extending forwardly and pivotally connected with said carriage in front of the roller so as to enable the roller to move into and out of impression relationship to a hectograph pad on said bed, yielding means adapted normally to hold said bracket in position with the roller out of operative position with respect to the hectograph pad so that a copy sheet may be manually positioned on said pad beneath said roller, and pressure means on said bracket for applying pressure downwardly and forwardly thereon for moving the roller downwardly against the action of said yielding means and for moving the carriage and its connected parts forwardly over the face of the pad.

4. In a duplicating apparatus, the combination of a flat bed, means for securing a hectograph pad removably in position on said bed, slide bars secured in parallel relation to each other along opposite sides of said bed, supporting blocks having a snug sliding fit on said bars, frame members connected with said slide blocks respectively, a transverse plate rigidly connected with said frame members, a yoke pivotally mounted on said transverse plate so as to swing about a transverse axis with respect thereto, a single roller rotatably mounted on said yoke so as to be movable into and out of operative pressure relation to said pad, a spring normally holding said roller out of operative relation to said pad, pressure means on said yoke for applying pressure downwardly and forwardly thereon for moving the roller downwardly against the action of said spring and for moving the yoke forwardly with respect to said pad and margin stop means located at the rear end of said bed against which a copy sheet may be positioned before pressure is applied to said yoke by the manual insertion thereof between said hectograph pad and said single roller.

5. In a duplicating apparatus, the combination of a bed in the form of a sheet metal plate having downwardly turned flanges about its edges, angle bars fixedly connected with the side flanges of the bed plate for reinforcing the plate, slide bars secured to said angle bars in outwardly spaced relation thereto along the sides of the bed, supporting blocks having a snug sliding fit on said slide bars, frame members in the form of housings pressed from sheet metal and connected with said slide blocks, a transverse plate extending at its ends into said housings and rigidly connected therewith in spaced relation to the end walls of the housings, a roller rotatably mounted on said transverse plate so as to be movable toward and from the bed plate thereon, springs operatively connected with said roller within said housings adapted normally to hold the roller out of operative position with respect to said bed plate, and pressure means operatively connected with said roller for forcing the roller downwardly and forwardly along said slide bars.

6. In a duplicating apparatus, the combination of a flat bed, slide bars secured in parallel relation to each other along opposite sides of said bed, a carriage transversely mounted for longitudinal movement on said slide bars, a roller pivotally mounted on said carriage and movable into and out of operative impression relationship to a hectograph pad on said bed, resilient means

for holding said roller normally out of operative position with respect to said pad, a pressure plate mounted in oblique position on said carriage for the application of downward and forward pressure to said roller, means for securing one end of a hectograph pad removably to said bed, and means for securing the other end of said hectograph pad to the forward end portion of said bed, comprising a plate slidably mounted on said bed and arranged for hooked engagement with said pad so as to tighten the pad by movement longitudinally of the bed, yielding means adapted normally to urge said plate in the direction for tightening the pad to take up any elongation of said pad caused by the application of pressure to said pressure plate, and cam means movably mounted on said bed adapted upon an operative stroke to move said plate against the action of said yielding means to such position as to permit said pad readily to be released from the plate and arranged so as to normally by its engagement with cooperating parts to be held against reverse movement and serving thus normally to hold the plate from movement again to position for tightening the pad.

7. In a duplicating apparatus, the combination of a flat bed, slide bars secured in parallel relation to each other along opposite sides of said bed, supporting blocks slidably mounted on said bars, a carriage extending across said bed and supported at opposite sides by said blocks, said carriage including frame members in the form of housings enclosing said supporting blocks and extending below the upper surface of said bed, means for securing one end of a hectograph pad removably to said bed, and means for securing the other end of said hectograph pad to the other end portion of said bed, comprising a plate slidably mounted on said bed and arranged for hooked engagement with said pad so as to tighten the pad by movement longitudinally of the bed, yielding means adapted normally to urge said plate in the direction for tightening the pad, an operating member movably mounted on said bed adapted in its inoperative position to permit said yielding means to hold said pad in tightened condition and adapted by movement into a predetermined operative position to move said plate in the direction for loosening said pad, and a handle on said operating member for moving said member into and out of operative position and extending from said operating member longitudinally beyond the end of said bed, the arrangement being such that said operating member normally is held by its engagement with cooperating parts against movement from its operative position so as to expedite connection of said pad with said plate.

8. In a duplicating apparatus, the combination of a flat bed, a carriage transversely mounted on said bed for longitudinal movement thereof, means for securing one end of a hectograph pad removably to one end of said bed, a retainer strip fixedly mounted on the bottom face of said bed at its opposite end portion having lugs projecting from its sides in slightly spaced relation to the face of the bed, a slide plate having a slot therein adapted to have a working fit on said retainer strip between the lugs and the bed plate and having notches in the sides of the slot adapted to permit said lugs to pass for assembly of the parts, means for connecting the forward edge of said plate removably with said pad, yielding means adapted normally to move said plate in the direction for tightening said pad, a

cam having substantially greater effective length than width pivotally mounted on said bed plate by means extending through the slot in said plate and arranged so that when in transverse position with respect to the bed it permits said yielding means to hold the pad in tightened condition and so that when moved into longitudinal position with respect to the bed it moves said plate in the direction for loosening said pad, and a lever connected with said cam for operation of the cam and extending from said cam longitudinally beyond the end of said bed, said cam being normally held by its engagement with cooperating parts against movement from its longitudinal position so as to expedite connection of said pad with said plate.

9. A carriage for a flat bed type of duplicating apparatus having slide bars mounted along the sides thereof, comprising a supporting block for cooperation with each of said slide bars, a frame member in the form of a housing associated with each of said supporting blocks and forming end walls and marginal side walls for said carriage, a transversely extending plate disposed

between said frame members and having upwardly bent ends, the edges of said ends meeting said marginal side walls and being affixed thereto whereby said upwardly bent ends form interior walls of said housings within which said supporting blocks are positioned, a bracket in the form of a yoke having arms at its end portions, said arms being pivoted on each of said upwardly bent ends within said housing, a roller journalled in said arms and positioned rearwardly of said bent up ends, resilient means positioned in one of said housings to maintain said roller in elevated position, and means associated with said bracket and positioned between said housings for manual depression of said roller in opposition to the action of said resilient means, said transversely extending plate being disposed forwardly of said roller and sloping downwardly toward said roller to form a copy sheet support whereby the space above said copy sheet support is entirely protected by said housings from said arms, said supporting blocks and said resilient means.

HUBERT JAGGER.
